(57) **CLAIM**

The ornamental design for a bar gun, as shown and described.

DESCRIPTION

FIG. 1 is a top plan view of a bar gun showing my new design;

FIG. 2 is a left side elevational view thereof;

FIG. 3 is a bottom plan view thereof;

FIG. 4 is a right side elevational view thereof;

FIG. 5 is a front elevational view thereof;

FIG. 6 is a rear elevational view thereof; and,

FIG. 7 is a perspective view thereof.

The drawing is lined for color. The broken lines in the drawings illustrate portions of the bar tool which form no part of the claimed design.
